UNITED STATES PATENT OFFICE

2,038,411

AUTOMATIC BLAST TORCH

Samuel C. Brody, Brighton, Mass.

Application August 18, 1934, Serial No. 740,476

11 Claims. (Cl. 158—35)

This invention relates to automatic blast torches of the type which embody a pressure generating unit comprising a casing adapted to contain liquid fuel, and either a wick tube extending from said casing or the casing extended in a manner enabling it to effectively hold a wick, and having a jet delivery opening, and a wick in said tube or casing having one end disposed in proximity to said jet delivery opening and its other end extending into the fuel within said casing.

Such torches are usually started by playing a starting flame on the wick tube in the vicinity of the jet delivery opening, the heat from said flame being conducted along said tube and to the fuel within said casing whereby to vaporize and/or gasify the same and when properly ignited to produce a reducing flame through said jet delivery opening.

When such torch is equipped with a combustion burner, the starting flame may be extinguished once the fuel in the casing of the pressure generating unit is sufficiently vaporized to generate pressure and the torch shall then continue to be self-generating without any further generating aid from the starting flame. When such torch is not equipped with a combustion burner, the starting flame must be constantly played upon the wick tube of the pressure generating unit to maintain such pressure generation.

In either type of torch, the goal to be attained is to keep the torch in satisfactory operation once it has been started, regardless of the position in which the entire torch unit may be held or placed while directing the reducing flame upon the work, or regardless of the vagaries of the wind, sudden drafts, or other factors calculated accidentally or unintentionally to extinguish the torch, and regardless of the degree or extent to which the pressure generating unit of the torch is inverted or in which position it may be placed.

Where the torch without a permeable barrier is shaken up and down or is used in a tilted or inverted position, the tendency of the raw, liquid, unvaporized or unvolatilized fuel is to rush into the burner tip or gas chamber and extinguish the torch by flooding or choking the same with raw, liquid, or unvaporized fuel.

Such rush of raw, unvaporized or liquid fuel towards the burner tip displaces the volatilized gases which normally fill the gas chamber or space in the region of the burner tip and which are necessary to cause the torch to generate pressure, mixing with said gases, and causing the torch to extinguish itself.

The established and successful method to overcome and prevent this interchange or mixing action has been accomplished by fixedly mounting a physical barrier at some point or place in the pressure chamber where it would serve and 5 coact with the wicking in the pressure chamber in the nature of a sort of plug or stopper or similar sort of packing made of permeable materials to form a permeable barrier which subdivides the pressure generating unit into sort of 10 a separate fuel and gas space or chamber. The feed wick was then threaded, attached or compressed to such a barrier, plug, or packing plug which while permeable to the gases volatilized when the torch was operating was retardant to 15 the free leakage of the liquid fuel therethrough or theretrap. By this construction, the raw, unvaporized or liquid fuel was prevented from rushing into the gas space or chamber when the torch was shaken, tilted or inverted, but the 20 volatilized gases could pass through said plug or packing barrier and escape at the jet delivery opening of the torch, thereby decisively eliminating the possibility of the volatilized or vaporized gases or vapors from mixing or mingling with 25 the raw, unvaporized or liquid fuel.

While I realize that my present invention is unquestionably dominated in principle by Patent No. 1,966,252 it nevertheless involves and introduces a new and novel method in the construction and arrangement of such a barrier within the pressure generating unit.

These differences in construction and/or arrangement make possible of attainment certain manufacturing and operating efficiencies, economies and constitute a desirable and certain advance in the art of automatic blast torch construction.

In the accompanying drawings, I have illustrated several of the many forms and arrangements contemplated by my invention.

In such drawings:—

Fig. 1 is a longitudinal section through the pressure generating unit of an automatic blast torch equipped with one form of my invention 45 designed to prevent the flooding, choking, or other extinguishment of the torch when shaken, tilted or inverted.

Figs. 2, 3, and 4 illustrate variants thereof.

Figs. 5 and 6 shown still further modification 50 and variants thereof.

Figs. 7 to 10 inclusive show further modifications and variants wherein I obtain an effective permeable barrier by squeezing, indenting, or pinching in the metal of the wick tube to com- 55

press the wicking of the generating unit at a point intermediate of both ends of said wicking.

Figs. 11 to 19 inclusive show arrangements whereby the wicking is so mounted and tensioned as itself to act as a permeable barrier in certain parts of its length or breadth, and

Figs 20 to 26 illustrate still further arrangements and variants for obtaining a permeable barrier at some selected point or zone within the pressure generating unit.

I have indicated generally at 10 the pressure generating unit of an automatic blast torch of standard construction. Such unit includes a fuel casing 11, a wick tube 12, a wick 13 in said wick tube and extending into the fuel contained in said casing, and a jet delivery nozzle 14 fixed within the outer end of said wick tube. Preferably although not necessarily the jet nozzle is in the form of a jet plug having a jet opening 15. Preferably, although not necessarily a combustion burner tube 16 is affixed over the outer end of the wick tube.

In all forms of my invention, I provide a barrier located between the ends or beyond the ends of the wick 12, which barrier is physically retardant to the free leakage therethrough or therepast of the raw, unvaporized or liquid fuel contained in the casing 11, but is permeable by the gases volatilized when the torch is operating, or being primed.

In Fig. 1, some part of the wick 13 is bunched or compacted tightly against some part of the wick tube wall 12, as indicated at 17, to furnish such a permeable barrier.

In Fig. 2, some part of the wick is knotted tightly against some part of the wick tube wall 12, as indicated at 18, to furnish such a permeable barrier.

In Fig. 3, some part of the wick 13 is bunched or compacted tightly against some part of the casing wall 11, as indicated at 19, to furnish a permeable barrier within the casing rather than within the wick tube, as in Figs. 1 and 2. The wick, where bunched or compacted at 19, provides a permeable barrier by reason of the fact that the turns or layers of the wick are arranged within the casing 11 as concentric or layer-around-layer, thereby filling in compacted form the entire internal circumference of the casing for a short distance vertically.

In Fig. 4, the wick is knotted, as at 20, rather than bunched as at 19 in Fig. 3, to furnish such a permeable barrier within the casing. The permeable barrier 17, 18, 19 or 20 sub-divides the blast torch into a vapor or gas space G and a fuel supply space F.

In Figs. 5 and 6 certain of the strands 21 of the wick, if a stranded wick is used, are threaded through holes 22 in a barrier 23 mounted within the pressure generating unit between the ends of the wick, the holes being smaller than the wick strands so that the strands are compressed somewhat, as graphically illustrated in Fig. 5.

Such barrier 23 may be mounted within the casing 11 in frictional contact with the wall thereof, or as an obvious variant which it is not considered necessary to illustrate, may be mounted within the wick tube 12 itself.

The material of the barrier 23 shown in Figs. 5 and 6 may be any material which is retardant to the free leakage of fuel therepast. On account of the many strands of wicking passing through the same, the barrier itself need not be gas-permeable, and hence may be made of such impermeable materials as steel, rubber or the like, but

through said barrier 23 coacting with the several wick strands strung therethrough, these wick strands thereby becoming effective as a permeable barrier.

Figs. 7 to 9 inclusive show arrangements where- 5 in the wick tube 12 is indented, bent, pinched in, or otherwise deformed to pinch or squeeze the wick and thereby compress or compact the same to form a permeable barrier, and Fig. 10 shows a still further variant wherein this result is obtained within the fuel casing 11 rather than within the wick tube itself, as in Figs. 7, 8, and 9.

In Fig. 7 the wick tube 12 is deformed at two points 24 which are staggered with reference to each other to compress or compact the wick 15 therebetween as a permeable barrier 25.

In Fig. 8, the wick tube is deformed at two opposite points 26 to produce the barrier effect in the wick at 27.

In Fig. 9 the wick tube is deformed at one 20 point 28 only to produce the barrier effect in the wick at 29.

In Fig. 10, the barrier effect in the wick is produced within the casing 11 by providing the wick tube within the casing with an extension 30. The 25 extension 30 is supported within the casing as at 31 and is deformed as at 32 to provide the barrier effect 33.

In Figs. 11 to 19 inclusive, I show arrangements for mounting, expanding and/or tensioning the wick in such manner as to cause it to exert a barrier effect through some part of its length.

In Fig. 11 the upper end of the wick is looped over a cross pin 34, the outer end of the wick 35 tube being formed interiorly thereof with a pair of diametrically opposite slots 35 extending longitudinally thereof from a point beginning at substantially the outer end of the jet plug 14 and extending inwardly a substantial distance beyond 40 the inner end of said plug. The ends of the pin 34 are disposed in said slots and seat on the shoulder 36 which results from providing the wick tube with the internal slots 35 so as to prevent the wick from slipping down beyond or from the place 45 where it is looped or fastened on the cross pin and also to prevent the pin itself from moving its position when the jet plug is screwed up flush to the cross pin.

Thus in the gas chamber or space between the 50 pin 34 and the inner face of the jet plug 14, which face is preferably concaved as best shown in Fig. 13, the wick 13 is compacted or compressed as a permeable barrier 37 (see Fig. 13).

By looping the wick over said pin 34 and drawing it to the proper degree of tautness the compacting or compressing effect in the barrier zone 37 may be varied at will.

In many cases, it is sufficient simply to mount the upper end of the wick as thus described. 60 When desired, however, the lower end of the wick may also be positively engaged and supported within the fuel casing 11, in which the tension on the wick and thus the degree of capillary action which the wick can exert may also be effectively regulated as well as the degree of permeability of the barrier.

Several methods of doing this are illustrated. In Fig. 11 the lower end of the wick is shown as 70 frictionally engaged under the free end of a spring clasp 38, the opposite end of which is fixedly mounted as at 39 upon the interior surface of the casing wall.

Preferably, although not necessarily, the clasp 75

38 extends horizontally of the casing 11 interiorly thereof.

Also, when desired, the clasp 38 may be pivoted as at 38a (Fig. 12) and the free end of the spring 5 clasp 38 may be positively but releasably latched over the wick. In such event, there is fixed to the interior of the casing wall in the path of flexing movement of the spring clasp a locking catch 40 (see Fig. 12) with which the free end 10 of said clasp is adapted to be engaged after the wick has been drawn to the desired tension and engaged under the spring clasp.

Alternatively, and as shown in Fig. 15, the lower end of the wick is extended in a tight manner 15 through a hole in a barrier 41, preferably of permeable material, which is adjustably supported within the casing adjacent the lower end thereof.

Various ways of adjustably supporting said barrier 41 will readily suggest themselves to those 20 skilled in the art. As illustrative of the many possibilities, I have shown the internal threads 42 for the usual threaded filling plug 43 at the bottom of the casing extended upwardly into the casing (see Fig. 15) for a substantial distance. 25 Coacting with such extended thread series is a fuel-tight threaded adjustment member 44 having in its outer face a screw driver slot 45 or its equivalent and having extending from its inner face a plurality of spaced supporting elements 30 46 for the barrier 41.

Thus there is provided between the members 41 and 44 a fuel space 47 into which the lower end of the wick depends through the hole in said member 41. The space within the casing 11 above 35 the member 41 is of course the gas space or chamber in this particular embodiment of my invention.

By removing the filler plug 43 and rotatively adjusting the fuel-tight member 44 inwardly or 40 outwardly along the casing 11, the tension on the wick and thus its capillary action may be regulated as desired.

In Fig. 16 I have shown the wick as mounted on a wire or other positioning element 48. The 45 upper end of the wick is assembled upon the upper end of the member 48 in such manner as to provide adjacent the inner end of the jet plug a compacted, compressed, or bunched wicking which acts as a permeable barrier portion 50. The upper end of the positioning element 48 is 50 bent outwardly to frictionally engage or wedge against the tube wall in the manner well known in the art and the permeable barrier portion 50 is engaged around such bent portion. The tightness of compaction of the wick in the region 50 may obviously be varied as desired.

In Fig. 17, I have shown an arrangement for obtaining the desired permeable barrier effect by simply crowding the wick so tightly within 60 the wick tube as to make of all or so much of the wick as desired within said tube a permeable barrier 51.

In Figs. 18 and 19, I show a still further variant of the method of positively mounting the 65 upper end of the wick in the wick tube.

In these figures, the same internal thread series 52 at the outer end of the wick tube to which the jet plug 14 is threaded is utilized to mount the adjustable wick supporting member 53 detailed in Fig. 19 in position within the wick tube 70 just below the jet plug.

This member 53 is opened up at two opposite faces, as indicated at 54 in Fig. 19 to expose an interior cross bar or pin 55 over which the upper 75 end of the wick is adapted to be looped. At

either side of the opened up places 54 the member 53 is formed as half-round surfaces which are exteriorly threaded as at 56 to coact with the internal threads 52 in the adjustment of the member within the wick tube. The upper or outer end of the member 53 extends as a top connecting web 57 which is provided with a screw driven slot 58 or its equivalent to enable the member to be conveniently adjusted.

By this construction, the wick is adjustably 10 supported at its upper end within the wick tube. That part of the wick 59 (see Fig. 16) which is 15 looped over the cross bar 55 acts as a permeable barrier within the gas chamber or space 60 which results in the member 53 from its unique combination of opened-up and threaded walls and top connecting web 57. This cross bar member has several new and novel points of effectiveness among which is one vital point of positively holding in an intendedly fixed position the end of 20 the wick attached or looped thereto so as to prevent the upper portion or end of the wicking from dropping down to a point below the usual area used for priming or preheating the generating unit. If this end of the wicking drops down 25 too far in the wick tube the generating tube then refuses to function so that it is not possible to satisfactorily operate the torch. My invention positively overcomes this condition for all time.

In Fig. 20 the upper end of the wick is knotted, 30 bunched or otherwise compacted adjacent to but slightly spaced away from the inner end of the jet plug whereby to form at such point a permeable barrier 61 and a gas chamber or space 62 between such barrier and the jet plug. 35

In Fig. 21 at approximately such point there is mounted a permeable barrier 63 of felt or the like, the gas space or chamber between said barrier 63 and the jet plug being indicated at 64.

In Fig. 22 the lower end of the wick is knotted, 40 bunched, or otherwise compacted within the casing 11, as indicated at 65 to form a permeable barrier sub-division the casing into a fuel space 66 and a gas chamber or space 67.

In Fig. 23, the lower end of the wick terminates in or near a barrier 68 mounted within 45 said casing 11 and subdividing the same into a fuel space 69 and a gas space or chamber 70. The barrier 68 is preferably of permeable material as felt or the like.

In Figs. 24, 25, and 26 the wick is supported within the wick tube by a positioning element in the nature of a wire rod or the like 71 preferably of highly heat-conductive material.

In Fig. 24 the positioning member 71 is embedded within the wick material, the wick at the upper end of said member being exposed as a bunched or compacted permeable barrier 72 disposed adjacent to but preferably spaced slightly away from the jet plug. 55

In Fig. 25, the upper end of the wick is so assembled with the member 71 that the upper end of the member 71 is exposed but the wick is bunched or compacted adjacent thereto as a permeable barrier 73. 60

In Fig. 26, the wick is so assembled with the member 71 that the act of drawing the same through the wick tube and into operating position causes the wick to be compacted in the wick tube as a permeable barrier 74. 70

In all three of these figures, viz. 24, 25, and 26 the member 71 is not necessarily but preferably a thin narrow flat strip of brass or like metal or composition.

In all forms, the action of the barrier, however 75

made or whatever way arranged within the pressure-generating unit is to prevent mixing or entering of the raw, unvaporized or liquid fuel in with or into the same chamber with the volatilized gases, should the torch be shaken, tilted or inverted, and hence to prevent intentional or accidental extinguishment of the reducing flame thereby enabling and freely permitting the pressure generating unit to operate at its best efficiency even when the torch is functioning in an upside-down position or in any inverted, tilted, or other desired position.

What I therefore claim and desire to secure by Letters Patent is:—

15. 1. In an automatic blast torch, the combination with a complete pressure-generating unit having a wick, of means frictionally engaging the wick at its upper end, and means frictionally engaging the wick at its lower end, said means coating 20 with each other for fixedly positioning or mounting the wick under regulated tension and capillarity within said pressure generating unit.
2. A device as claimed in claim 1 wherein a portion of the wick is compacted to provide 25 a barrier which is permeable to the vapors or gases volatilized when the torch is operating but is retardant to the free passage or leakage of the raw or liquid fuel therethrough or therepast.
30. 3. In an automatic blast torch, a pressure generating unit comprising a casing adapted to contain liquid fuel, a wick tube extending from said casing and having a jet delivery opening, and a wick in said tube and extending into the fuel 35 within said casing, said wick having a compacted portion providing a permeable barrier disposed in contacting relation with a wall of the torch to thereby sub-divide the blast torch into a vapor or gas space and a fuel supply space, said barrier being permeable to the gases volatilized when the torch is operating but being retardant to the 40 passage or free leakage of raw or liquid fuel therethrough or therepast.
45. 4. An automatic blast torch as claimed in claim 3 wherein the wick is folded once over upon itself to form such compacted permeable barrier and wherein the wick is supported at said fold by a cross member disposed within the wick tube adjacent to but below or back of the jet delivery opening.
50. 5. An automatic blast torch as claimed in claim 3 wherein the wick tube is deformed to compact the wick within that area of the wick which is included within said deformed part of the wick tube.
55. 6. An automatic blast torch as claimed in claim 3 wherein the wick is positioned within the wick tube by means of a positioning member extending longitudinally of the wick and bent with the

wick intertwined or interwound therewith to frictionally engage and wedge against a wall of the torch thereby forming the compacted portion of the wick which constitutes the permeable barrier.

5. 7. An automatic blast torch as claimed in claim 3 wherein the wick tube is interiorly threaded adjacent its outer end and wherein a cage-like member supports the upper end of the wick and is provided with an external series of screw threads 10 adapted to engage the internal screw-threads at the wick tube and with an internal cross-bar over which the upper end of the wick is engaged.

8. In an automatic blast torch, a pressure generating unit comprising a casing adapted to contain liquid fuel, a wick tube extending from said casing and having a jet delivery opening, and a wick in said tube and extending into the fuel within said casing, said wick having a compacted portion providing a permeable barrier disposed in contacting relation with a wall of the torch to thereby sub-divide the blast torch into a vapor or gas space and a fuel supply space, said barrier being permeable to the gases volatilized when the torch is operating but being retardant to the passage or free leakage of raw or liquid fuel therethrough or therepast, wick engaging means disposed within the upper end of the wick tube and adjustable longitudinally therealong, and wick-engaging means disposed adjacent the lower end of the casing and effective with said first-named means to regulate the tension of the wick at will thereby changing at will the degree of capillary attraction of the wick and the degree of permeability of the permeable barrier means. 30

9. An automatic blast torch as claimed in claim 8 wherein the wick-engaging means at the lower end of the casing is a spring clasp and the wick is frictionally and adjustably engaged under the free end of said spring clasp.

40. 10. An automatic blast torch as claimed in claim 8 wherein the wick-engaging means at the lower end of the casing is a spring clasp and the wick is frictionally and adjustably engaged under the free end of said spring clasp, and wherein a locking catch is provided for releasably latching the free end of said spring clasp.

11. In an automatic blast torch, a pressure generating unit comprising a casing adapted to contain liquid fuel, a wick tube having a portion extending into said casing, said extension having a deformed portion and a wick in said tube and compressed at said deformed portion of the wick tube to provide a barrier which is permeable to the gases volatilized when the torch is operating but retardant to the passage or free leakage of raw or liquid therethrough or therepast.

SAMUEL C. BRODY.
